SCAFFOLD

John J. Masterson, Williamstown, N. Y.

Application October 4, 1930. Serial No. 486,428

6 Claims. (Cl. 304—19)

This invention relates to scaffolds, and it is an object of the invention to provide an apparatus of this kind adapted to be suspended from horizontally disposed beams of a building structure, bridge structure, and the like, and which includes securing or anchoring means whereby the scaffold may be effectively maintained in desired location.

Another object of the invention is to provide an apparatus of this kind including a hanger adapted to be operatively engaged with an I-beam, U-beam or the like, or with the rivets of a plate beam.

Furthermore, it is an object of the invention to provide an apparatus of this kind including a hanger adapted to be placed in desired working position and which is constructed in a manner to permit the same to be shifted as desired along its support.

The invention consists in the details of construction and in the combination and arrangement of the several parts of my improved scaffold whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view partly in elevation and partly in section illustrating a scaffold constructed in accordance with an embodiment of my invention and in operative engagement with horizontally disposed I-beams;

Figure 2 is a sectional view taken substantially on the line 2—2 of Figure 1, looking in the direction of the arrow;

Figure 3 is an enlarged fragmentary view partly in section and partly in elevation illustrating a hanger in operative engagement with the bottom flange of an I-beam;

Figure 4 is a sectional view taken substantially on the line 4—4 of Figure 3;

Figure 5 is a fragmentary sectional view taken longitudinally through one of the beam engaging plates particularly illustrated in Figure 3 showing the means whereby the hanger may be shifted when desired along the beam;

Figure 6 is a fragmentary view in inside elevation of one of the side members of the hanger illustrated in Figure 3;

Figure 7 is another sectional view taken longitudinally through the beam engaging plate;

Figure 8 is a fragmentary view partly in section and partly in elevation illustrating the hanger in operative engagement with the rivets of a plate beam;

Figure 9 is a view partly in section and partly in elevation illustrating a hanger in operative engagement with a channel beam;

Figure 10 is a fragmentary elevational view of the supporting trackways comprised in the scaffold as herein disclosed together with a co-acting carriage;

Figure 11 is a view in top plan of the carriage as particularly illustrated in Figure 10 unapplied, the cross planks being omitted;

Figure 12 is a transverse sectional view taken substantially through the central portion of the structure as illustrated in Figure 10, certain of the parts being in elevation.

As particularly illustrated in Figures 1 to 3 inclusive, B denotes one of a series of horizontally disposed I-beams such as comprised in building structures of different kinds, and it is the purpose of the present invention to provide means whereby a scaffold can be readily suspended from said beams to facilitate the painting of such beams or the surfaces adjacent thereto although the scaffold may be employed, as is believed to be obvious, for other purposes.

My improved scaffold, as illustrated in Figures 1 to 3 inclusive, comprises a pair of suitably placed substantially parallel inverted T-beams T each of desired length and each of which has its opposite end portions suspended from the base flanges 1 of a beam B. Pivotally connected with the vertical flange 2 of a beam T at a desired point therealong is a rigid elongated suspender 3 comprised in a hanger structure H. The suspender 3, as herein disclosed, comprises two sections having their inner end portions in overlapping relation and fixedly connected one to the other by bolts 4 or the like.

These bolts 4 are adapted to be selectively disposed through the longitudinally spaced openings 5 in the inner portions of the sections of the suspender 3 so that said suspender may be lengthened or shortened as desired.

The upper end portion of the suspender 3 is formed to provide an elongated head 6 which is pivotally connected by the bolt 7 between the lower plates 8 carried by the side plates 9 of the hanger. These plates 8 are inwardly offset with respect to the plates 9 and each of said plates 8 and 9 is connected by an intermediate integral

plate 10 disposed on a required inward incline so that in the complete assembly of the hanger the plates 8 will snugly receive therebetween the heads 6 of the suspender 3.

- 5 Each of the plates 9 is provided substantially at its transverse center with an opening 11 in which is received an end portion of an inwardly disposed arm 12, said arm 12 being pivotally secured to the plate 9 by the pin 14 or the like.
- 10 The arm 12 of one plate 9 is adapted to lap the arm 12 of the second plate 9 and the overlapping portion of each of these plates is provided with a series of longitudinally spaced openings 15 through which are adapted to be selectively inserted suitable tie pins 16 whereby the plates 9 may be held in desired spaced relation in accordance with the requirements of practice. The arms 12 when connected provide means whereby the plates 9 are supported for swinging movement one toward the other.

15 The upper or outer longitudinal marginal portion of each of the plates 9 is provided therealong with an inwardly disposed flange 17, the under edge of which is undulated, as indicated at 18, 20 with the ends of the flange 17 provided with the inwardly disposed bevels 19.

25 The flange 17 with the undulating under edge 18 permits the hanger to be readily employed in connection with a plate beam as illustrated in Figure 8, and in a manner whereby the flanges 17 may be effectively engaged over the outstanding heads 20 of the plate rivets, thus providing means for suspending the scaffold from a beam P of this type. The bevels 19 permit the hanger to be readily shifted along the beam P over the heads 20 and more especially when the flanges 17 have been swung in a direction away from the opposite side faces of the beam P in a manner which will be hereinafter more particularly referred to.

30 In the embodiment of the invention as illustrated in Figures 1 to 3, however, the undulating under edge 18 of the flange 17 is adapted to interlock with a similarly undulated upstanding flange 21 carried by the outer marginal portion of an anchor plate 22 which is adapted to have direct contact from above with the upper surface of a flange 1 of a beam B. This plate 22 is of desired dimensions and at its outer corner portions is provided with the outwardly directed and laterally disposed lugs 23 having disposed therethrough openings 24. These openings 24 are adapted to register with the openings 25 provided in the upper corner portions of a plate 9 and through which suitable securing screws or the like are intended to be engaged whereby the plate 22 may be employed as a part of the adjacent plate 9 but readily disengaged or freed therefrom when not required.

35 The plate 22 adjacent its opposite ends is provided therethrough with the elongated slots 26 which are adapted to receive from above the rollers 27 carried by a plate 28 overlying the plate 22. The plate 28 has freely disposed through its opposite end portions the bolts 29 in threaded engagement with the plate 22. Upon proper rotation of the bolts 29 the rollers 27 will be forced through the openings 26 to bring said rollers in direct contact with the upper surface of a flange 1 which is of importance and advantage when it is desired to shift the hanger along the beam B. When the hanger, however, has been moved to desired position, the bolts 29 are rotated in a direction to lift the rollers 27 out of contact with a flange 1 and thus allowing the plate 22 to come

in direct close contact with such flange 1 to assure the hanger effectively retaining its desired location.

40 In Figure 9 is illustrated an embodiment of the invention wherein the hanger is especially designed for use in connection with a channel beam. In this embodiment one of the plates 9' coacts with a flange 1' of a beam B' through the medium of a plate 22' as hereinbefore described with respect to the invention as particularly illustrated 45 in Figures 1 to 3 of the drawings. The plate 9' through the instrumentality of the intermediate plate 10' is connected to an inner plate 8'. This plate 8' is pivotally connected by the bolt 7' or its equivalent with the head 6' of a suspender 3'. The bolt 7' also provides a pivotal mounting for a straight side plate 30, the upper marginal portion of which, when the hanger is in applied position, overlies a side face of the beam B' and said upper or overlying portion of the plate 30 50 loosely carries a roller 31 having direct contact with said adjacent side face. The plate 9' together with the plate 30 are provided with the coacting arms 12.

55 The upper marginal portion of the plate 30 is defined by an outwardly arranged reverted flange 32 providing a hook member whereby, if desired, the plate 30 may be horizontally disposed and rested from above upon the upper flange of the beam B' with the hook member 32 in locking engagement with the free marginal portion of said upper flange of the beam B'. When in such position a suitable suspender is adapted to be engaged with the plate 30 through the opening provided therethrough for the passage of the bolt 7' 60 although the connection of such a suspender may be effected in any desired manner.

65 Coacting with each of the beams T is a carriage C as particularly illustrated in Figures 10, 11 and 12. This carriage C comprises a pair of elongated side bars 33 having their central portions connected by an interposed plate 34, said plate 34 and said side members or bars 33 being preferably integral. The extremities of the bars or members 33 are continued by the upstanding posts 35 terminating in the inwardly disposed trunnions 36. Freely mounted on the trunnions 36 are the wheels 37 having contact from above with the bottom flanges 38 of a beam T. By this means the carriage C may be readily and conveniently shifted along a beam T as may be necessary.

70 The outer extremities of the side members or bars 33 are preferably connected by the transversely disposed bars 39 to avoid the liability of said outer extremities of the side members or bars 33 separating.

75 The plate 34 constitutes a table which has mounted thereon a saddle 40, the central portion of which is pivotally connected by the bolt 41 or the like to the plate or table 34 whereby said saddle may be adjusted at different angles with respect to the longitudinal axis of the carriage C as may be required. The saddle 40 is intended to provide a support for the transverse planks 42 or the like comprised in the scaffold structure. By having the saddle 40 supported for pivotal or swinging movement, it is possible that the planks 42 be disposed on such angles as may best comply with the requirements of practice and particularly in such cases wherein a carriage of one beam T cannot be transversely aligned with the carriage of a second beam T.

80 The weight of the beams T together with that of the load carried thereby serves normally to maintain the suspenders 3 in a vertical position 85

with the heads 6 of each of the suspenders snugly engaged between the plates 8. This engagement of the heads 6 between the plates 8 results in the upper marginal portions of the plates 9 having effective coaction with the associated beam. The side faces of the head 6 are beveled or converge one toward the other in cross section to provide a wedge portion 43. Upon pull being imposed upon the suspender 3 in one direction 10 this wedge portion 43, with respect to the plates 8, will recede at one side of the bolt 7 and enter between such plates 8 at the opposite sides of the bolt 7 whereby the plates 8 will move inwardly resulting in the upper portions of the plates 9 having slight outward swinging movement to 15 allow the desired shifting of the hanger along a beam. As the suspended 3 returns to vertical position the wedge portion 43 will coact with the plates 8 in a manner to return the upper portions 20 of the plates 9 to effective coaction with the associated beam.

To facilitate the action of the head 6, I find it of advantage to have the opposed faces 8a of the plates 8 disposed on a bevel substantially 25 complementary to the beveled side faces of the wedge portion 43 of the head 6.

It will be noted that in my improved scaffold the carriages C are adapted to be shifted in a direction angular to the direction of the supporting beams B or their equivalent, thus providing means whereby said beams may be readily and conveniently painted or otherwise worked upon. This is equally true in connection with a building structure or a bridge structure access to 35 which is now generally difficult.

From the foregoing description it is thought to be obvious that a scaffold constructed in accordance with my invention is particularly well adapted for use by reason of the convenience and 40 facility with which it may be assembled and operated, and it will also be obvious that my invention is susceptible of some change and modification without departing from the principles and spirit thereof, and for this reason 45 I do not wish to be understood as limiting myself to the precise arrangement and formation of the several parts herein shown in carrying out my invention in practice except as hereinafter claimed.

50 I claim:—

1. A hanger for a scaffold comprising two plates provided with inwardly disposed flanges, means connecting said plates for relative swinging movement and maintaining said plates in spaced 55 relation, and a suspender supported by the plates, said suspender having means coacting with means on the plates for moving the plates one with respect to the other upon movement of the suspender in one direction.

60

65

70

75

2. A hanger for a scaffold comprising two plates provided with inwardly disposed flanges, means connecting said plates for relative swinging movement and maintaining said plates in spaced relation, a suspender supported by the plates, an anchoring plate coacting with one of the plates and having a portion underlying the flange of said one of the plates, and means for securing said anchoring plate and flange one to the other. 80

3. A hanger for a scaffold comprising two plates provided with inwardly disposed flanges, means connecting said plates for relative swinging movement and maintaining said plates in spaced relation, a suspender supported by the plates, an anchoring plate coacting with one of the plates and having a portion underlying the flange of said one of the plates, means for securing said anchoring plate and flange one to the other, and lifting means carried by the anchoring plate. 85

4. A hanger for a scaffold comprising two plates provided with inwardly disposed flanges, means connecting said plates for relative swinging movement and maintaining said plates in spaced relation, a suspender supported by the plates, an anchoring plate coacting with one of the plates and having a portion underlying the flange of said one of the plates, means for securing said anchoring plate and flange one to the other, and lifting means carried by the anchoring plate, said lifting means including rollers. 90

5. A hanger for a scaffold comprising two plates, means for connecting the intermediate portions of the plates for rocking movement one toward the other, said means also maintaining said plates in spaced relation, inwardly disposed flanges carried by the corresponding extremities of the plates, and a suspender pivotally engaged with the opposite end portions of the plates, said suspender and the adjacent portions of the plates having coacting means for rocking the plates in one direction upon swinging the suspender in one direction. 100

6. A hanger for a scaffold comprising two plates, means for connecting the intermediate portions of the plates for rocking movement one toward the other, said means also maintaining said plates in spaced relation, inwardly disposed flanges carried by the corresponding extremities of the plates, and a suspender pivotally engaged with the opposite end portions of the plates, the pivoted portion of the suspender being of a wedge formation extending beyond opposite sides of the pivot, the adjacent faces of the plates being beveled similar to the side faces of the wedge. 105
